UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

AUTOMATIC AIR AND WATER CONNECTION FOR WATER TUBES.

Application filed August 7, 1925. Serial No. 48,759.

This invention relates to rock drills, but more particularly to an automatic air and water connection for fluid actuated rock drills of the hammer type.

- 5 One object of the invention is to insure an adequate supply of cleansing fluid, either water or pressure fluid, to a drill hole and to prevent intermingling of such fluids during the normal operation of the drill.
- 10 Another object is to automatically open communication between a pressure fluid supply and a water tube for cleansing a drilled hole when the pressure of the water supply reaches or falls below a certain predetermined value.

Other objects will be in part obvious and in part pointed out hereinafter.

- 20 The invention consists of the combinations of elements, features of construction, and arrangement of parts having the general mode of operation substantially as hereinafter described and more particularly pointed out in the appended claims and illustrated in the accompanying drawing.

- 25 The figure in the drawing is a sectional elevation, of so much of a rock drill as will serve to illustrate the invention.

Referring more particularly to the drawing, the invention is shown embodied in a rock drill having a cylinder A sealed at its rear end by a back cylinder washer B which also serves to centralize a back head C with respect to the cylinder A. The cylinder A and the back head C may be held in operative relation with respect to each other by any suitable means, such means preferably consisting of side bolts (not shown). A reciprocatory hammer piston D is provided for the cylinder A for delivering blows of impact to a drill steel (not shown).

In order to provide rotative movement to the piston D for preventing binding of the drill steel within the drill hole, a fluted rifle bar E engages the piston in the usual manner. A ratchet head F preferably formed integrally with the rifle bar E carries a plurality of spring actuated pawls G adapted to engage teeth H carried by a ratchet ring J when the piston moves in one direction, but which will pass freely over the teeth H when the piston moves in the opposite direction. In this way the piston which may be connected against relative rotation with the drill steel in any well known and suit-

able manner will be caused to describe a 55 partial revolution on alternate strokes.

The throttle valve K rotatable in the back head C is connected with a supply of pressure fluid and controls the admission of pressure fluid to the drill. The distribution of 60 pressure fluid may be controlled by any suitable valve, in this instance, a spool valve L is indicated. The valve L is adapted to reciprocate in a valve chest O preferably formed integral with the cylinder A and in 65 this instance bushings P and Q provide a seat for the valve L. The bushings P and Q are preferably unsymmetrical with respect to each other to prevent improper insertion of said bushings into the valve 70 chest O. For this reason a screw threaded plug R is formed eccentrically on the bushing P and extends through a bore S of the valve chest. A nut T is screwed on the plug R of the bushing P to hold said bushing 75 against endwise movement in the chest O. Somewhat similar means are provided for insuring proper insertion of the bushing Q. Accordingly, a projection U is formed eccentrically on the outer end of the bushing 80 Q and cooperates with a bore V of the back head C to prevent rotation of the bushing within the valve chest.

The valve L has an enlarged central head W which controls an inlet gap X between 85 the inner ends of the bushings P and Q through which pressure fluid passing from the throttle valve K through a main supply passage Y passes into the interior of the bushings P and Q. Supply passages Z and 90 b provide communication between the interior of the bushings P and Q and the front and rear ends respectively of the cylinder A.

In order that the valve L may be quickly and positively reciprocated within the bushings P and Q, pressure chambers c and d are formed in the ends of the valve. A passage e formed diagonally through the valve provides communication between the chamber c and the interior of the bushing Q. 100 Similarly, a passage f is formed preferably diagonally through the valve to provide communication between the interior of the bushing P and the chamber d through the valve. By forming the passages e and f as 105 described, a portion of the pressure fluid passing to one or the other of the ends of the cylinder will pass through one or the

- other of the diagonal passages *e* and *f* into the interior of the valve for throwing the valve to one of its limiting positions, either forwardly or rearwardly when the piston 5 nears the end of its stroke depending upon the direction in which the piston is moving. A main exhaust port *g* provides an escape for the pressure fluid from the cylinder and is controlled by the piston *D*.
- 10 Means are provided for removing the cuttings from the drill hole. To this end a water tube *h* is arranged through the drill and is supported at one end in the back head *C*. A threaded recess *j* is formed in the back head *C* to receive a correspondingly threaded plug *k* into which the water tube *h* extends and whereby said water tube is held in position. The plug *k* is preferably provided with a recess *o* to receive a packing *p*, which may be of rubber or other suitable material, to cooperate with a collar *q* of the water tube *h* for preventing leakage along said tube and also to provide a yielding support for the water tube. A plate *r* arranged beneath the collar *q* and about the water tube *h* serves as a rigid support for the water tube in one direction and extends partly into the recess *o* to insure perfect sealing about said tube. In order to prevent excessive wear between the plate *r* and the bottom of the recess *j*, a washer *s* preferably of soft material is inserted between said plate and the bottom of the recess. The plug *k* is provided with flats *t* to receive a wrench 35 whereby said plug may be readily screwed into and out of the back head *C* and preferably extends somewhat beyond the back head to receive a back head cap *u* to seal the recess *j*.
- 40 Means are provided for supplying cleansing liquid, usually water, to the water tube. To this end a connection *v*, which may be of any suitable form, is screwed into the back head *C*. The connection *v* in this instance 45 communicates with the water tube *h* through a passage *w* in the back head and through a longitudinal exterior groove *x* in the plug *k*, and through the water plug cap *u* and a passage *y* formed in the plug *k*.
- 50 To the end that the drill hole may be properly cleansed during the drilling operation in case the pressure of the cleansing liquid or water becomes reduced to a value inadequate for efficient cleansing, or fails through 55 other reasons, pressure fluid may be automatically substituted for removing the cuttings from the drill hole. Accordingly, a bore *z* is formed in the back head *C* and has a reduced portion 2 which communicates 60 with the main supply passage *Y* through a passage 3. A passage 4 provides communication preferably between the inner end of the bore *z* and the water connection *v*. At the juncture of the bore *z* and the reduced portion 2, a valve seat 5 is formed to accommo-
- date a reciprocating needle valve 6. In this instance, the needle valve 6 is provided with a stem 7 to serve as a guide for a spring 8 inserted between said valve and a sealing plug 9 for holding said valve on the seat 5. A plurality of longitudinal grooves 10 are preferably formed throughout the length of the perimetric surface of the valve 6 to permit water under pressure to enter the bore *z* and act against the outer end of said valve to augment the force of the spring 8 for holding the valve on the seat 5.
- During the operation of the drill, assuming that the force of the spring 8 together with the pressure of the cleansing water against the outer portion of the valve 6 exceeds the value of the pressure fluid acting against the inner end or face of the valve, water will flow from the connection *v* through the passage *w* and the groove *x* into the cap *u* and thence through the passage *y* in the plug *k* and through the water tube *h* to the drill hole. If, however, the pressure of the cleansing water should become reduced to a value sufficiently low to enable the pressure fluid acting against the inner face of the valve 6 to overcome the pressure acting against the outer end of the valve, the valve 6 will be raised from the seat 5 and pressure fluid will flow through the passage 4 and through the passages described as the course of the cleansing water. Pressure fluid thus flowing through the passage 4 will intermingle with the water in the connection *v* and will accelerate the flow of the water, thus assuring an adequate supply of cleansing fluid to the drill steel. In the event that the water supply should fail entirely, or should become cut-off for other reasons, a constant supply of pressure fluid will flow to the drill hole until a preponderance of pressure may again be obtained rearwardly of the valve 6. The valve 6 will then be forced to its seat and water alone will serve as the cleansing medium.
- The advantages of the invention reside in the fact that a constant supply of cleansing fluid to the drill steel is at all times insured. This is particularly advantageous in cases where water alone is preferred as a cleansing agent, and which under normal conditions may be supplied to the drill steel without intermingling with the pressure fluid, which is often desirable.
- I claim:
1. In a fluid actuated rock drill, the combination of a back head with a throttle valve in the back head, a source of pressure fluid supply communicating with the back head and controlled by the throttle valve, a water tube in the back head, a connection secured to the back head for conveying water under pressure to the water tube, a bore between the throttle valve and the water connection, a seat in the bore, a passage leading from

one side of the seat to the connection, a passage leading from the other side of the seat to the throttle valve, and a spring pressed valve reciprocable in the bore to normally cooperate with the seat for preventing communication between the passages.

2. In a fluid actuated rock drill, the combination of a back head with a throttle valve in the back head, a source of pressure fluid supply communicating with the back head and controlled by the throttle valve, a water tube in the back head, a connection secured to the back head for conveying water under pressure to the water tube, a bore in the back head and having a reduced portion, a

needle valve in the bore, a seat for said valve, a spring for holding said valve on the seat, a passage leading from the bore to the connection for admitting water under pressure to the bore to augment the force of the spring for normally holding the valve on the seat, and a passage in communication with the throttle valve leading to the reduced portion to admit pressure fluid to said portion for unseating the valve and supplying pressure fluid to the water tube when the water pressure falls to a certain predetermined value.

In testimony whereof I have signed this specification.

CHARLES C. HANSEN.
